UNITED STATES PATENT OFFICE.

CHARLES N. CORYELL, OF MAMARONECK, NEW YORK.

VANITY CASE.

Application filed December 20, 1923. Serial No. 681,792.

To all whom it may concern:

Be it known that I, CHARLES N. CORYELL, a citizen of the United States, and resident of Mamaroneck, in the county of 5 Westchester and State of New York, have invented certain new and useful Improvements in Vanity Cases, of which the following is a specification.

This invention relates particularly to 10 vanity boxes of the "watch case" type and some of the more important objects are to provide for the carrying of all the usual accessories, such as the face powder and rouge compacts, puffs and mirror in a condensed, attractive form convenient for 15 handling and readily accessible for use; which further can be inexpensively produced and easily and quickly assembled.

In the drawing accompanying and forming 20 part of this specification there is illustrated an embodiment of the invention wherein the foregoing and other objects are attained and in which, Figure 1 is a plan view of the case.

Figure 2 is a side or edge view of the same.

Figure 3 is a plan view showing the case 25 opened and with parts broken away and appearing in section for purposes of better illustration.

Figure 4 is an enlarged cross sectional view on substantially the plane of line 4-4 of Figure 1.

Figure 5 is a fragmentary sectional view 30 on substantially the plane of line 5-5 of Figure 1.

The body of the case consists of complementary cover sections 7, 8 of generally circular outline and dished to enclose a 35 compartment space.

The upper cover section 7 is shown provided at one edge with a pair of spaced hinge knuckles 9 formed by a pair of integral lugs turned over to provide eyes for 45 a hinge pintle and bent back against the inside of the cover, as indicated at 10 in Figure 4. This cover section is also shown as having an angularly projecting annular rim or flange 11 from which a finger-hold 12 is struck out at a point opposite the hinge.

The lower cover section is shown formed with a bead 13 curled over about the rim of the same, of an inside diameter to receive and frictionally hold the flange 11 of

the top cover and having a gap or notch 14 in the hinge side of the same just long enough to receive the two hinge knuckles 9 of the other cover.

A mirror 15 is shown hingedly secured 60 between the two covers by means of a single hinge knuckle 16 disposed in the space between the knuckles 9 of the top cover.

The pintle is provided in the illustration by a wire 17 passed through the three 65 hinge knuckles and extended at both sides in substantially circular form so as to lie within the bead of the lower cover section.

With this construction it will be seen that to pivotally connect the parts it is 70 simply necessary to pass the pintle wire through the aligned hinge knuckles of the top cover and mirror and then after bringing the notch in the lower cover over the outer hinge knuckles to spring the curved 75 terminals of the wire in under the curled edge of the lower cover.

The face powder is shown in the form of a compact 18 carried by a shallow dish 19 seated in the lower cover and held therein 80 by being engaged beneath the hinge knuckles at one edge, at 20, and beneath the inwardly bent end 21 of the pintle wire at the opposite edge. This construction enables the powder compacts being inserted 85 by simply dropping one edge of the dish under the knuckles and then bringing the opposite edge down under the holding tongue on the end of the wire.

The rouge is shown in the form of a compact 22 having a beveled edge 23 held by the beveled flange 24 on a dished annular plate 25 which snaps into the dependent flange 11 of the upper cover and is cut away at one edge at 26 to engage behind the hinge 95 knuckles. This compact holding ring at one edge overlies the inturned portion 10 of the lug which provides the spaced hinge knuckles 9 so as to reinforce the same and the opposite edge of the ring is exposed at 27 at the 100 outwardly turned finger-hold 12 to afford a grip for springing the ring out of the cover when a refill is to be inserted.

In the construction illustrated the mirror is shown as carried by an annular frame 28 and as held in place therein by a disheled washer 29 sprung beneath the inturned annular flange 30 surrounding the frame. The hinge lug 16 for the mirror is shown formed as a part of this mirror frame and the mir- 110

ror holding washer is indicated as engaged with the end of this lug at 31. This construction affords an easily assembled and inexpensive construction for mounting the 5 mirror.

The flange 30 of the mirror frame is made of a size to fit snugly and snap within the annular flange 11 of the top cover. This reinforces the flange 11 and insures of its snapping firmly into place within the bead 13. This causes the mirror to stay within the upper cover when the case is opened and therefore stand in position for use when the face powder is being applied from the lower 10 cover and then when the rouge is to be used, the mirror is simply swung down into the lower cover section, as in Figure 3, where it can be seen while taking the rouge from the upper cover section. The puffs for applying 15 the face powder and rouge are ordinarily carried in the case between the respective compacts and the mirror intermediate the same where they are ready for use as soon as the cover is opened.

25 To facilitate disengagement of the mirror from within the confining flange 11, the flange of the mirror frame may be indented to afford a finger-hold 32 and this indented portion may be made with a shoulder 33 as 30 shown, to the more firmly secure the mirror confining ring therein. This depressed finger-hold in the mirror frame also, it will be seen in Figure 3, provides clearance for the inturned compact holding lug of the pintle wire.

With the construction shown the parts are readily assembled and secured firmly together without soldering, riveting or resorting to the use of special fastening means, the 40 contained articles are instantly available and the mirror is positioned so that it may be used interchangeably with either one or the other of the compacts. The beveled holding means for the smaller compact secures that firmly in place and holds it against rattling and the dish mounting of the other compact provides a flat form of compact which requires no special molding and which can easily be held in place by means of the extension on the pintle wire.

The connection of the spaced hinge knuckles 9 by the integral end portion 10 braces these knuckles and overcomes any spreading tendency of the same, thus 45 strengthening the device as a whole and assuring free hinging movements of the two case sections and the intermediate or mirror section.

What I claim is:

50 1. In a vanity case, cooperating case sections and an intermediate section, registering hinge knuckles on the intermediate section and one of the case sections, the other case section having a curled edge recessed 55 to receive the hinge knuckles and a pintle

wire extended through the hinge knuckles and seated in the curled edge of the one case section.

2. The structure of claim 1 in which the intermediate section contains a mirror and 70 in which the case sections are each provided with means for confining a compact therein.

3. The structure of claim 1 in which one case section has a flange to spring inside 75 the bead of the other case section and in which the intermediate section has a frictional engagement within said flange.

4. The structure of claim 1 in which the pintle wire has an inturned portion to hold 80 a compact and in which the intermediate section has a finger-hold depression in line with said inturned portion.

5. In a vanity case, cooperating case sections, one having a hinge knuckle and the other having a curled edge recessed at one point to receive said hinge knuckle and a pintle wire extending across the recess and through the knuckle positioned therein, said wire being seated within the curled edge 90 of the case section and extended a substantial part of the periphery of said case section and thereby held by spring engagement within the curled edge.

6. In a vanity case, cooperating case sections, one having spaced hinge knuckles and the other having an inwardly curled edge recessed to receive said knuckles, an intermediate section having a single hinge knuckle positioned between the spaced 100 knuckles of the one cover section and a pintle wire seated within the curled edge and extending through the aligned hinge knuckles of the other two sections.

7. In a vanity case, cooperating case sections, one having a pair of hinge knuckles connected in spaced relation by an integral extension turned back against the inside of 105 said case section and the other having a bead receiving said hinge knuckles and a pintle wire engaged within the bead and extending across the recess through said connected hinge knuckles.

8. In a vanity case, cooperating case sections, one having a pair of hinge buckles connected in spaced relation by an integral extension and the other having a bead receiving said hinge knuckles, a pintle wire engaged within the bead and extending 110 across the recess through said connected hinge knuckles and an intermediate section having a knuckle engaged on the pintle wire in the space between the connected hinge knuckles, said integral extension bridging 115 across the knuckle of the intermediate section and holding the spaced hinge knuckles properly positioned at opposite sides of the same.

9. A vanity case having a hollow cover 120 provided with an edge flange, a bevel edge 125

compact seated in said cover with its back supported against the inside of the cover and a retaining annulus sprung within the flange of said cover and having a beveled flange overlying the beveled edge of the compact to thereby hold the compact against the inside of the cover.

10. In a vanity case, cooperating case sections hingedly connected by a spring pintle wire extending peripherally within the rim of one of the cover sections, said wire having an inturned spring portion substantially opposite the hinge connection and a compact sprung into the case section beneath said inturned spring portion of the pintle wire.

11. In a vanity case, cooperating case sections hingedly connected by a pintle wire extending peripherally within the rim of one of the cover sections, said wire having an inturned portion substantially opposite the hinge connection, a compact sprung into

the case section beneath said inturned portion of the pintle wire and an intermediate section hinged between the case sections and having a finger-hold depression in line with the inturned portion of the pintle wire to clear the same when the intermediate section is turned into the case.

12. A vanity case having hinged case sections and a hinged mirror frame provided with an annular inturned flange, a mirror seated in said frame and a dished washer sprung into the frame over the mirror and beneath the inturned flange, the flange having a finger-hold depression in one side thereof opposite the hinge providing a shoulder engaged with the mirror securing washer.

Signed at New York, in the county of New York and State of New York, this 10th day of December, A. D. 1923.

CHARLES N. CORYELL.
